UNITED STATES PATENT OFFICE.

WILLIAM ERNEST TURNER, OF DENTON, NEAR MANCHESTER, ENGLAND.

FELT-HAT-BRUSHING MACHINE.

1,100,460.

Specification of Letters Patent.

Patented June 16, 1914.

Application filed December 9, 1913. Serial No. 805,662.

To all whom it may concern:

Be it known that I, WILLIAM ERNEST TURNER, a subject of the King of Great Britain and Ireland, and resident of Denton, near Manchester, England, have invented certain new and useful Improvements in Felt-Hat-Brushing Machines, of which the following is a specification.

This invention refers to and consists of a new or improved construction of machine for use in brushing felt hat bodies and the like, the machine being chiefly for use in raising the nap in the making of what are known as "brush" or "velour" fur hats.

According to the invention the machine comprises essentially an arrangement of three rollers rotating adjacent to the periphery of a rotary and, by preference, longitudinally reciprocating brush revolving in or above a vessel containing liquor, the arrangement being such that the rollers both feed the hat bodies to the brush and return them to the front of the machine, while they also present the hats to the brush at the most effective angle or position to be acted upon for the purpose of raising the nap.

On the accompanying drawings, Figure 1 illustrates a transverse sectional elevation (in part) of the machine. Fig. 2 illustrates (in part) a front elevation of the machine.

a^1 , a^2 are the end frames of the machine while b^1 , b^2 are the cross rails or stays secured to the end frames.

c^1 , c^2 , c^3 are the feed rollers, the upper roller being, preferably, slightly larger than the other rollers. The rollers are, preferably, rubber-covered and are journaled in inclined brackets or end frames a^3 supported from the sides a^1 , a^2 of the machine.

d is the brush which is mounted in bearings supported on the end frames a^1 , a^2 .

The rollers c^1 , c^2 , c^3 are adjustable relatively to each other, that is to say, the upper and lower rollers c^1 , c^3 are capable of movement toward or from the roller c^2 and the adjustments may be such as to allow of only a slight pressure being put upon the hat bodies. Springs e normally hold the rollers in contact with each other, while the adjusting screws e^1 , e^2 serve to allow for the pressure being increased or diminished as required.

In front of the lower roller c^1 is a copper covered feed table f from which the hat bodies to be treated are fed to the rollers. The brush d as shown, is arranged to rotate

in a tank g containing hot liquor (usually acidulated water), while a guard or cover h prevents the liquor being thrown off the brush d as it revolves. The liquor in the tank is heated by a steam coil g^1 . The floor of the tank is provided with a drain outlet g^2 closed by a plug g^3 . It may, however, be fitted with a ball cock and overflow. The brush d is driven from shaft i by means of a crossed belt. The rollers c^1 , c^3 are driven from shaft i , via chain j , sprocket wheel k on stud l , further chain j^1 , further sprocket wheel c^5 and equal sized spur pinions c^4 on the ends of the rollers, see Fig. 2. The brackets a^3 carrying the roller bearings are adjustable by means of screws a^5 toward and away from the brush d . This adjustment allows for the regulation of the brush action. The brush d is rotated in a reverse direction to the roller c^2 and at a higher speed. The brush d may have a rotary motion only, but it will preferably also have a longitudinal reciprocating movement. This may be obtained by means of a grooved cam i^1 on the shaft i and a lever or connecting rod m fulcrumed at m^1 and having a stud or bowl at one end engaging the groove in the cam, while its other end is forked or suitably shaped to engage a groove in the brush spindle d^1 or a collar thereon. Thus, under the rotation of the shaft i , the brush will receive a to and fro longitudinal motion as well as a rotary motion.

In proceeding to treat a felt hat body, it is fed in a flattened state between the lower pair of rollers c^1 , c^2 . After passing between these rollers the hat body passes upward and between the rollers c^2 and c^3 see Fig. 1 back into the operator's hand, or on to a further copper covered table f^1 arranged above the table f . While so traveling from the lower to the upper rollers and around the middle roller, the felt is held stretched while the brush d , which is traveling at a higher speed but in the reverse direction, acts upon it to raise the nap. While brushing the hat body the brush also imparts the hot liquor to the hat, the brushing, heat and moisture ensuring of a practically permanent set being given to the raised fur. The rollers c^1 , c^2 , c^3 lie one slightly in advance of another, see Fig. 1 so that their surfaces will approximately follow the curvature of the brush, and so also that the top roller c^3 will practically leave no space between it and the brush and thereby compel the hat body to

pass back between the middle and top rollers instead of passing over the brush.

The machine will usually be wide enough to allow of several hat bodies being passed 5 through simultaneously. In some cases the bath of hot liquor will not be used and reliance will be placed on the brushing only.

While describing the machine as applied for brushing felt hat bodies, it will be understood 10 that it is also applicable for "carrotting" furs and the like for use in hat manufacture.

What I claim is:—

In a felt hat or like brushing machine 15 comprising in combination three rollers one above another and slightly in advance of one another and in yielding contact with each other, the top roller being slightly larger than the other two rollers, a rotary cylindrical brush arranged parallel with and im- 20

mediately behind the rollers, means for rotating the top and bottom rollers in the same direction and the middle roller in the reverse direction, causing a hat passed between the bottom and middle rollers at the front of the machine to pass around and over the middle roller and be delivered again at the front of the machine, means for imparting a rotary motion to said brush, opposite in direction to that of the middle roller and for 25 simultaneously reciprocating same transversely, causing it to act upon one side of the hat as it is passed around the middle roller, substantially as described.

In witness whereof I have hereunto set 30 my hand in the presence of two witnesses.

W. ERNEST TURNER.
